UNITED STATES PATENT OFFICE.

WILLIAM JOHN LYND, OF YREKA, CALIFORNIA.

SPEAKING AND SINGING DOLL.

SPECIFICATION forming part of Letters Patent No. 351,785, dated November 2, 1886.

Application filed February 17, 1886. Serial No. 192,311. (No model.)

To all whom it may concern:

Be it known that I, WILLIAM JOHN LYND, a resident of Yreka, county of Siskiyou, State of California, have invented a new and useful 5 Improved Speaking and Singing Doll; and I hereby declare that the following is a full, clear, and exact description of the same, reference being had to the accompanying drawings.

10 My invention consists in a certain construction and combination of parts, as hereinafter set forth and claimed, forming a device or article by means of which sound from the human voice can be made to appear to proceed from 15 a figure or doll.

The following description fully explains the nature of my said invention and the manner in which I proceed to construct, apply, and operate the same, the accompanying drawings 20 being referred to by figures and letters.

Figure 1 is a vertical section of a doll's head, showing a longitudinal elevation of a speaking-tube. Fig. 2 is a view showing the application of a speaking-tube to a doll and 25 the manner of operating the same.

In applying the speaking-tube to a doll, I employ a tube of any required length, made of rubber, copper, or other suitable material. The section of the tube *b*, inserted in the doll's 30 head *a*, is made in the form of an ordinary horn or trumpet, the diameter increasing gradually from the point of junction *c* to the flaring mouth of the tube, which is placed near the doll's mouth. The end of the tube which is 35 inserted in the doll's head will be provided with an inside thread, if it is made of metal, to connect with the end *c* of the outside section of the tube *d*, which has a uniform diameter of about one inch and any required length. 40 The tube *e* extends from the rear of the doll's head for a suitable distance, to be applied to the operator's or speaker's mouth. The free end of the outer section of the tube, whether

of rubber or metal, will be provided with a mouth-piece, *h*, the aperture of which must be 45 of equal diameter with the tube.

To prevent the escape of the sound of the operator's voice, and to facilitate its delivery in volume, I provide a mouth-cover, *f*, made of light leather or other suitable stuff, open 50 for the passage of the tube, which is applied between the nostrils and chin of the operator, and is drawn tight over the tube and kept in place by an elastic band, *g*, attached to the mouth-cover and extending round the operator's head, Fig. 2.

The mouth of the doll should be open, and if the nostrils are also open the delivery of sound will be increased. The lips may be rendered movable by some simple mechanism; 60 but I prefer that they should be rigid.

When in operation, the operator holds the tube *e* in hand, and through the mouth-piece *h* speaks or sings, shouts or cries, and the sound produced is heard from the mouth of the doll, 65 which seems to speak, sing, shout, or cry, as the case may be.

I am aware that tubes have been placed in the heads of figures and extended out to be spoken into at the opposite end and emit the 70 sound from the head of the figure, and I do not claim such, broadly.

Having thus fully described my invention, what I claim, and desire to secure by Letters Patent, is—

75 The combination, with a doll, of the section or trumpet-mouthed tube *b*, placed in the head of the doll and opening at its mouth, the tube *e*, having the hood or cover *f* for placing over the operator's mouth, the mouth-piece *h*, and 80 securing-cord *g*, all substantially as and for the purpose set forth.

WILLIAM JOHN LYND. [L. S.]
